ABSTRACT OF THE DISCLOSURE

Alkoxybenzamide analgesics are introduced into the systemic circulation system via a contiguous mucous membrane to increase onset of activity, potency, etc.

BACKGROUND OF THE INVENTION

The present invention relates to a means of alleviating pain and, more particularly, to a method of, and formulations for, introducing alkoxybenzamides into the systemic circulation system.

The conventional method of introducing analgesic substances into the systemic circulatory system is through oral ingestion and the gastro-intestinal tract. However, as explained in Drill's Pharmacology in Medicine, 3rd edition, McGraw-Hill, New York, N.Y. (J. S. D. Palma, editor), pp. 297-298, salicylates and derivatives thereof are subject to chemical alteration in the liver. The chemical alteration of the alkoxybenzamide molecule reduces the potency of the drug. On the other hand, the poor solubility of alkoxybenzamides in common fluids for injection (e.g., normal saline, dextrose for injection and the like) prohibits the use of alkoxybenzamides in an injectable form, other than that of a dilute suspension, with any degree of safety or confidence in humans. Therefore, experiments concerned with the parenteral use of alkoxybenzamides such as ortho-ethoxybenzamide in humans for analgesic activity have not been performed. However, it has now been discovered that alkoxybenzamides can be introduced into the systemic circulation system through mucous membranes when the membrane is contiguous to a large supply of blood to provide a route of administration comparable to that of the parenteral route of administration. Thus, for example, in the article entitled "Investigations of o-Ethoxybenzamide (Ethosalicyl) a New Salicyl Derivative" by F. Ducco, S. de Vercelli and R. Strobbia, published in *Gazetta Medica Italiana*, 114, No. 5 (1955), pp. 93-99, it was reported that the effective oral dosage of o-ethoxybenzamide to relieve the pain of acute articular rheumatism, arthritis, etc., was in the range of one to four (1-4) grams. It has been shown that when contacted with a mucous membrane such as that of the oral cavity in the form of a sublingual tablet the effective analgesic dose is in the range of fifty to two hundred (50-200) milligrams, i.e., in the range of 0.71 to a maximum of 4 milligrams per kilogram, that is the efficacy of the o-ethoxybenzamide is increased at least twenty times (1000/50=20). Furthermore, in a

2

sub-lingual toxicity study of three months duration data was obtained tending to establish that the mucosal method of administration of alkoxybenzamides precludes the possibility of an overdose.

SUMMARY OF THE INVENTION

As those skilled in the art know the alkoxybenzamides can be represented by the following formula:

15 where R is an alkyl group having 1 to 5 carbon atoms.

Representative, and presently the most readily obtained of the alkoxybenzamides is ortho-ethoxybenzamide (o-ethoxybenzamide or OEB) represented by the formula:

20 Accordingly, OEB has been chosen as the representative of the alkoxybenzamides because it is commercially available and representative of the class defined hereinbefore.

The present method and formulations of alkoxybenzamides for introducing alkoxybenzamides into the systemic circulation have a number of advantages of the methods and formulations known heretofore. These advantages are enumerated as follows:

- 35 (1) Rapid onset of drug activity with minimum dosage.
- (2) Reduction in side effects.
- (3) More potent action from the drug because it is not chemically altered by the liver before arrival at the site of action.
- 40 (4) Smaller dosage required since the transmucosal adsorption is rapid and complete in contrast to gastro-intestinal adsorption in which only about fifty (50) percent of the drug is adsorbed within six hours. (C. Davidson, J. Wangler and P. K. Smith, *J. Pharm. Exp. Therap.*, 136, pp. 226-231, 1962.)
- (5) The drug can be administered at any time and no special need such as water is required.
- (6) The analgesic action of the drug is much greater than that of salicylates and phenacetin-like drugs and does not cause gastro-intestinal irritation.
- 50 (7) The experimental analgesic activity of the drug is comparable to certain narcotic drugs, e.g., codeine, but still is not a narcotic and does not possess the toxic side effects of narcotics.
- (8) By administration through contact with a mucous membrane the drug is especially beneficial in relieving pain and in particular pain due to skeletal muscular origin.
- (9) The drug can be administered to patients unable to take analgesics per se.

60 The most readily accessible mucous membranes contiguous to large supplies of blood are the mucous membrane of the oral or buccal cavity, that of the lungs, the mucous membrane of the rectum and that of the vagina.

Thus, the present method of the formulations for, administering alkoxybenzamides provides introduction of the benzamide directly into the arterial circulation without involvement of the upper gastrointestinal tract, intravenous or other parenteral routes of administration. The advantage of the present method is that passage of the drug through the liver is prevented prior to arrival of the drug at the site of action. Degradation of the drug readily occurs at this site, i.e., the liver, therefore results in a reduction of the available active molecules. The present method of contacting a mucous membrane contiguous to the systemic circulatory system assures a greater adsorption of the intact molecule of the drug into the arterial vascular network and therefore a larger retention of the intact molecules of the drug for delivery to sites within the central nervous system resulting in the induction of analgesia. For introduction into the systemic circulatory system through a mucous membrane contiguous thereto, such as the lungs, either a solution of the alkoxybenzamide suitable for use with a nebulizer or an aerosol formulation is used. For introduction through the oral mucous into the systemic circulatory system a sub-lingual tablet or lozenge can be used. For introduction into the systemic circulatory system through the mucous membrane of the vagina or the rectum suppositories or tablets can be used.

DESCRIPTION OF THE PREFERRED EMBODIMENTS

Formulations for introducing alkoxybenzamide by any of the foregoing methods are illustrated by the formulations of o-ethoxybenzamide set forth in Table I.

VI—Powders

VII—Lotions

VIII—Creams.

It has been shown that ortho-ethoxybenzamide when given by the aerosol inhalation route to animals is also capable of inducing sedative-analgesia at a level greater than that elicited by the gastro-intestinal route and at least about equal to that produced by parenteral administration.

The maximum possible dose of the ortho-ethoxybenzamide when given by the aerosol inhalation route is determined by confining a test animal in a chamber. The maximum possible dose is calculated from the following relationship where

C=concentration of the drug in the material sprayed into the chamber,

D_{AeI} =AeI dose in milligrams per kilogram,
 R_v =Respiratory volume in millimeters per minute, for a mouse, 20 ml./min.,
 T =Exposure time,
 V_e =Volume of exposure chamber,
 K_w =Kilograms of body weight,
 V =Amount of material sprayed into the chamber.

10 Then the AeI dose in milligrams per kilogram is

$$D_{AeI} = \frac{R_v \cdot T \cdot C \cdot V}{V_e} \cdot K_w$$

15

Thus, the dosage in 10% propylene glycol solution to provide protection in 50% of the mice subjected to the phenylquinone writhing assay by the three routes is given in the following comparison:

20

Route:	Mg./kg.
Oral-gastro-intestinal	6.2
Intra-peritoneal	3.2
25 Aerosol (by Chamber Method)	4.2 maximum possible.*

30 *Those skilled in the art readily understand that all of the drug sprayed into the exposure chamber is not inhaled by the subject animal. However, the value given is based upon the total amount of material sprayed into the chamber.

The problem of providing an aerosol spray for inhalation of ortho-ethoxybenzamide involves finding a solvent

for the drug. The solubility of ortho-ethoxybenzamide in three solvents is set forth in the following tabulation:

65 Solvent: Maximum concentration, percent

Water (cold)	0.05
Water (hot, about 100° F.)	0.10
Ethanol (hot)	5.00
Propylene glycol (hot)	2.00

70 It is manifest that hot ethanol is the best solvent. On the other hand, a mixture containing more than about 18% of ethanol by weight produces an unpleasant oral reaction which can more than counterbalance the efficacy of the inhalatory route. Therefore, the solvent for the ortho-ethoxybenzamide in addition to being a solvent for

75

the drug must possess these other characteristics (1) it must be a solvent for lipoids and nonpolar materials; (2) it must be non-toxic; and (3) it must be well tolerated by the organism.

¹ A detailed description of this method is given Proc. Soc. Exp. Biol. Med. 95, 729 (1957) E. Siegmund, E et al.

² The denominator is the number of test animals; the numerator is the number of test animals reacting.

³ Mg./kg. as usual is milligrams of OEB per kilogram of animal body weight.

HOT PLATE REFLEX

This reflex is an extension of the flexor withdrawal response, e.g., the occurrence of a painful stimulus results

in the animals' attempt to escape. The stimulus employed is a thermal one. This standard procedure originally was devised by Woolfe and MacDonald and reported in J. Pharmacol. Exp. Therap. 80, 300 (1944) in a paper entitled "The Evaluation of the Analgesic Action of Pethidine Hydrochloride (Demerol)."

Orthoethoxybenzamide supplied by four manufacturers was tested. The OEB was administered by the low pressure aerosol inhalation route (nebulizer) with the results as indicated hereinafter. The test mice were exposed for five minutes employing a 0.4% to 0.8% solution as indicated.

SPONTANEOUS MOTOR ACTIVITY

Spontaneous motor activity was determined for mice by employing the Woodward Activity Recorder. The Woodward activity instrument consists of three separate circular units each having a diameter of twelve inches and a circular housing five and one-half inches in diameter which contains a photoelectric cell and six ports. Spontaneous motor activity is registered as a function of the number of times the light beam from each of the ports is interrupted by placing three mice in each unit for up to sixty minutes and recording the number of times the light beams were interrupted fifteen minutes after administration of the drug and at the end of sixty minutes. The results are presented in Table IV.

¹ Intraperitoneal.

² It is known that at low dosage levels certain central nervous system depressant drugs, i.e., phenobarbital, do not produce depression, but do exhibit excitement. The excitement produced by aerosol administration (low dosage level due to incomplete adsorption from the administration chamber) is analogous to that produced by phenobarbital at low doses.

³ Aerosol inhalation (employing nebulizer).

7
SKIN TWITCH REFLEX

The skin twitch reflex in rabbits is based essentially upon the principle that the latent response of the skin to twitch, when an electrical stimulus is applied, is a function of the animal's sensitivity threshold. The stimulus is delivered through bipolar platinum electrodes spaced one centimeter apart to the dorsal skin of the animal. The power source is a Thomas Square Wave Stimulator which delivers a direct current square wave pulse at 120 c.p.s. with 0.3 msec. pulse delay. Each animal is prepared by cleanly shaving the hair from the dorsolumbar area with an electric clipper. Four concentric sites one centimeter in diameter are demarcated with indelible ink; two on either side of the middle. The response time is recorded by the observer employing a stop watch. The alkoxybenzamide, in this instance orthoethoxybenzamide, was administered by placing a mask over the rabbit's face, introducing the OEB into the mask from a nebulizer, and allowing the rabbit to inhale the drug for a period of five (5) minutes. The assigned dose is an approximation. The results are set forth in Table V.

25

In the high pressure aerosol inhalation method of administering alkoxybenzamides (high pressure relative to the pressure of a nebulizer) a propellant or propellants is used. The propellant(s) and the solvent(s) preferably are mutually soluble. The propellant(s) must be non-toxic, must evaporate so rapidly as to produce a relatively dry spray with the result that only dry material, i.e., substantially only the alkoxybenzamide reaches the transport sites, i.e., the mucous membranes of the mouth, trachea, bronchia, and lungs including the alveolar sac.

30 The propellant(s) preferably is the liquefied normally gaseous low molecular weight halogenated hydrocarbons, such as halogenated ethane, methane, and/or mixtures thereof. The halogenated hydrocarbons known in the art 35 as the "Freons" and "Genetrons" and the like have been found to be particularly suitable. Specific examples of such propellants are dichlorodifluoromethane (Freon 12), dichlorotetrafluoroethane (Freon 114), trichloromonofluoroethane (Freon 11), trifluoroethylchloride and monochlorodifluoromethane (Freon 22). In general, any fluorinated hydrocarbon propellant or combination of fluorinated hydrocarbon propellants or compressed gas, e.g., 40 nitrous oxide, carbon dioxide, compatible with a suitable co-solvent system and approved for food and/or drug application can be used. In addition to the propellant-solvent characteristics given hereinbefore, the solution of the particular propellant-solvent should be integrated with the type of container and the particular vapor pressure desired.

50 55 Illustrative of the variation in solvents and in propellant composition which have been tested are the following compositions:

TABLE VI

Component	Sample No.									
	1	2	3	4	5	6	7	8	9	10

Absolute alcohol, percent wt.....	18.0	9.0	.....	18.0	9.2	9.0	.....	18.0	18.0	.....
Propellant:										
Solvent A, percent wt.....	40.0	40.0	40.0	35.0	40.0	66.0	80.0	68.0	60.0	68.0
Solvent B, percent wt.....	40.0	40.0	40.0	35.0	40.0	6.0	10.0	12.0	10.0	12.0
Solvent C, percent wt.....	.....	.....	.....	.....	.....	8.0	8.0	10.0	10.0	.....

Propellant-solvent A is trichloromonofluoromethane. Propellant-solvent B is dichlorodifluoromethane.

Propellant-solvent C is trifluoroethyl chloride.

Sample numbers 1 and 2 have a tendency to crystallize but this is slight.

Sample number 4 tends to separate into two distinct layers. However, it is easily dispersed with shaking and operative if shaken before using.

Sample number 5 is satisfactory though hazy.

Sample number 6 is satisfactory.

Sample numbers 7 and 8 are satisfactory although each has a tendency to settle into two layers but each is readily dispersed with shaking.

Sample numbers 9 and 10 are satisfactory.

The aerosol compositions samples 1 through 10 were dispensed through Emson M-20 PFG metering valves discharging 50 milligrams of the aerosol composition per actuation. The calculated dosages for the four most satisfactory combinations of ingredients are as follows:

Sample No.:	Dosage per actuation, mgs.
5	1.14
6	1.44
9	1.20
10	1.16

The concentration of the drug is limited by the concentration which can be dispensed through a specific valve and by its solubility in the propellant-solvent system. For example, for discharge through Emson M-20 PFG valves the limiting concentration for ortho-ethoxybenzamide is about 2%.

From the foregoing it is manifest that the aerosol composition comprises about 2% by weight of ortho-ethoxybenzamide, propellant-solvent 70 to 98% by weight, and auxiliary solvent or co-solvent the balance to make 100%.

Suspensions of alkoxybenzamide in excess of two percent and the balance propellant or propellant-solvent can be used employing valve systems such as the Newman-Green or Valve Corporation of America.

Pharmacological evaluation has shown that ortho-ethoxybenzamide given by aerosol inhalation to mice will adequately protect them from writhing induced by an intra-peritoneal injection of para-phenylquinone and also significantly elevate their thermic skin tolerance time threshold. When compared with dosages of the drug in which the non-“Freon” propellant system was employed equivalent dosages in a solvent system such as exemplified by the propellant solvent systems of Samples No. 9 and 10 in Table VI were found to produce effects which were comparable. The formulation of ortho-ethoxybenzamide in a solvent system such as described hereinbefore represents a means by which a relatively poorly soluble substance can be dissolved in the propellant solvent system and administered via the aerosol inhalation route.

laxants, e.g., maprobamate, styramate or Librium (Chlordiazepoxide HCl).

The aerosol analgesic composition of the present invention provides rapid onset of action with minimal dosage, reduced side effects, and a convenient and esthetically more attractive form of medication.

SUB-LINGUAL TABLET

It has been demonstrated in the study upon which the present invention is based on that the sublingual and/or buccal administration of orthoethoxybenzamide using a tablet with rapid disintegration capabilities facilitates the absorption of the drug through the oral mucosa directly into the systemic circulatory system. This action results in an augmentation of the pharmacological action of the drug beyond that which could be anticipated by the conventional use of oral ingestion and absorption through the gastro-intestinal tract.

The efficacy of the route of administration provided by the sublingual tablet has been demonstrated and may be related to the rapid absorption and transportation of the drug to its locus of action before going to the liver where it is chemically altered. The intactness of the drug molecule and its delivery to the site of action are directly related to the route of administration. Moreover, this route of administration, because of its augmenting action on potency, allows for a reduced amount to be employed for therapeutic value. Therefore, this route of administration reduces the possibility of side effects. Thus, the advantages of the use of a sublingual tablet for the administration of orthoethoxybenzamide are (1) rapid onset of drug activity; (2) more potent and prolonged actions from the drug because it is not chemically altered by the liver before arriving at the site of the action; and (3) a reduced amount is required since oral trans-mucosal absorption is complete within minutes in contrast to gastro-intestinal absorption in which about fifty percent of the drug is absorbed within six hours.

The sublingual administration of orthoethoxybenzamide has the following advantages over the oral method of administration previously recommended; (1) the drug can be administered at any time without any need for assisting means such as potable water to wash the drug from the mouth, (2) the action of the orthoethoxybenzamide in smaller doses is much greater than that of orally administered salicylates and phenacetin-like drugs and does not cause gastro-intestinal irritation; (3) the analgesic effectiveness of the drug is comparable to that of certain narcotic drugs, e.g., codeine, but without the hazards of the narcotic side effects, (4) the administration of orthoethoxybenzamide by this route is especially beneficial in relieving pain which is refractive to salicylates and other non-narcotic agents.

Illustrative formulations which have provided satisfactory results are as follows:

TABLE VII

It is within the purview of the present invention to incorporate other analgesic drugs, e.g., acetylsalicylic acid; anti-histamines, e.g., chlorpheniramine, Benadryl; [2-(diphenylmethoxy)-N,N-dimethyllethylamine hydrochloride]; bronchodilators, e.g., isoproterenol, ephedrine; sedatives, e.g., pentobarbital; centrally acting muscle re-

75 It is to be noted that formulations 4, 5 and 6 containing no PVP exhibit greater disintegrating capabilities than the formulation 1 in which there is PVP. Further, formulation 6 represents a more refined and acceptable dosage form. It provides improved tablet disintegration, due to addition of micro starch and flavor improvement enhances aesthetic value. These capabilities augment drug

absorption; substitutions and additions to the formula can be made as required.

There can also be incorporated in the sublingual tablet, in addition to the alkoxybenzamide, therapeutic amounts of steroids, antihistamines, broncho-dilators, parasympatholytic and antitussives and other drugs which may be absorbed sublingually or via the gastro-intestinal tract if delayed and additional absorption is desired: steroids, dexamethane sulfate; antihistamines, chloropheniramine maleate; bronchodilator, isoproterenol parasympatholytic agent, atropine sulfate; and antitussant, dextromethorphan HBr are examples of drugs that may be added to the formulations.

Those skilled in the art will recognize that the sublingual tablet of the present invention comprises a therapeutic concentration of alkoxybenzamide, a disintegrating agent such as starch, a densifier such as PVP, an excipient such as lactose, sucrose, and a die lubricant such as magnesium stearate.

The composition of the sublingual or buccal cavity tablet can be within the ranges set forth as follows:

TABLE VII

Component:	Milligrams per tablet
Orthoethoxybenzamide	About 10 to about 100.
Polyvinylpyrrolidone	Zero to about 2.5.
Starch, arrowroot	About 7 to about 14.0.

TABLE VIII

	Formulation Number							
	I	II	III	IV	V	VI	VII	VIII
Aerosol (fluorinated hydrocarbon type)	Aerosol nebulizer type	Sublingual tablets	Suppositories	Suspensions	Powders	Lotions	Creams

NOTE.—For:

Absolute ethanol—Ethanol USP can be used.

Propylene glycol—Absolute ethanol or Ethanol USP can be used in whole or in part. Monofluorotrichloromethane—Dichlorotetrafluoroethane, trichlorotrifluoroethane, trifluoroethylchloride. Ethanol USP can be used in whole or in part.

Difluorodichloromethane—Difluoromonochloromethane, octofluorocyclobutane can be used in whole or in part.

Microstarch—Arrowroot starch, potato starch, purified talc can be used in whole or in part.

Magnesium stearate—Sodium stearate, talc, stearic acid can be used in whole or in part.

Urea—Sulka Floc (purified cellulose), aminoacetic acid, carboxymethylcellulose acid can be used in whole or in part.

Cyclamate sodium—Hexamic acid, sucrose, mannitol can be used in whole or in part.

Saccharine sodium—Saccharine calcium can be used in whole or in part.

Sorbitol solution—Glycerin can be used in whole or in part.

Polyethylene glycol 1000—Theobroma oil, polyethylene glycol 1540, polyethylene glycol 6000, glycerine, gelatin can be used in whole or in part.

Mineral oil—Olive oil, glycerin, cottonseed oil can be used in whole or in part.

Glycerol monostearate 165—Sodium Oleate, triethanolamine oleate can be used in whole or in part.

Component:	Milligrams per tablet
Magnesium Stearate, U.S.P.	About 0.5 to about 1.0.
Lactose, U.S.P.	Zero to about 50.0.
Cyclamate Sodium, N.F.	Zero to about 20.0.
Saccharine Sodium, U.S.P.	Zero to about 5.0.
Flavors	Zero to about 10.0.
Starch, micro	Zero to about 15.0.
Urea, N.F.	Zero to about 10.0.

Incorporation of other analgesic drugs, steroids, anti-histamines, broncho-dilators, parasympatholytic, antitussive, sedative, and/or muscle relaxants in any or all of the formulations set forth herein can be made.

For introducing alkoxybenzamides in which the alkoxy group has not more than five carbon atoms into the systematic circulatory through mucous membranes contiguous thereto as illustrated hereinbefore or through the skin in addition to the nebulizer solutions, aerosol mixtures, and the sublingual tablet specifically described hereinbefore suppositories, suspensions, powders, lotions and creams supplying an adult dose in the range of about fifty (50) to about two hundred and eighty (280) milligrams, i.e., about 0.71 to about 4 milligrams per kilogram of body weight can be used. Thus, for example, using commercially available orthoethoxybenzamide, formulations in the ranges set forth in Table VIII are useful.

As stated hereinbefore, there is evidence that the administration of alkoxybenzamides through the mucosa precludes the possibility of an overdose. The foregoing statement is corroborated by the following data involving acute human toxicity studies and chronic and sub-chronic animal studies.

(1) Acute human toxicity studies via the sublingual route, at doses ranging up to 2,500 to 3,000 mg. per subject have been performed involving 12 healthy males. The drug was administered under monitored conditions and did not produce overt toxic responses.

(2) Chronic and sub-chronic toxicity studies involving dogs which received up to 600 mg./kg. of the drug sublingually, have revealed no obvious toxic behavioral manifestations.

(3) Chronic toxicity studies involving rats wherein the drug is given by oral ingestion have revealed some influence on body weight gain rate.

(4) The dog and rat experiments are being carried out simultaneously and therefore the apparent toxic effect by

for the most part demonstrated less drug available in the blood at the 5 and 180 minute interval.

TABLE IX

5	Animal	Time sample withdrawn		Results
		Colony No.	Test No.	
10	233-----	A ₁		15 Trace of aromatic compound.
		A ₂		30 Do.
		A ₃		60 None detected.
15	234-----	B ₁		15 Do.
		B ₂		30 Do.
		B ₃		60 (*)
20	212-----	C ₁		15 None detected.
		C ₂		30 Do.

*Since more than one aromatic compound can absorb ultraviolet light at the same wave length and since also the plotted curve from the sample B₃ was not distinct or specific for the peak absorbance obtained, it can only be stated that an aromatic compound or compounds as a concentration of 18.0 mcg./ml. of plasma were present.

TABLE X

Dog No.	Weight, lbs.	Dose, gm.	Mg. percent blood level/given time (after drug introduction)							
			5-10 min.		30 min.		60 min.		3 hour	
			Sub ¹	Oral	Sub	Oral	Sub	Oral	Sub	Oral
304M-----	24	{1.0 {5.0	0.89 (2)	0.0	0.0	1.40	1.04	1.60	1.97	0.0

¹ Sublingual.

² Trace.

oral ingestion would be indicative that sublingually the drug is self limiting.

(5) The effectiveness of sublingual application of the drug is supported by the following experiments in dogs.

(a) Three dogs, two treated with the drug sublingually and one control dog treated with placebo material, sublingually were selected from a chronic toxicity study colony. The treated dogs had received the drug over a six months interval and are currently receiving 600 mg./kg. The drug was found in the blood of the treated animals but none was found in the blood of the placebo treated animal.

(b) Four sibling dogs of the same litter (Table X) were administered doses of 50, 100 and 500 mg./kg. by both oral and sublingual routes. Blood samples were taken from the jugular vein at 5, 30, 60 and 180 minutes past administration.

The blood samples from animals which received the drug sublingually provided detectable amounts of the drug at the 5 through 180 minute intervals whereas the same animals given the drug orally at the same dosage

What is claimed is:

1. A method of administering ortho-ethoxybenzamide which comprises introducing into the oral cavity to contact a mucous membrane contiguous to the systemic circulatory system a composition comprising a therapeutically effective amount of ortho-ethoxybenzamide in a non-toxic pharmaceutical carrier adapted to provide rapid and substantially complete absorption of said ortho-ethoxybenzamide when in contact with said mucous membrane, said composition being in the form of a sublingual tablet.
2. A method as set forth in claim 1 wherein said amount of ortho-ethoxybenzamide is sufficient to provide a dose of at least 50 milligrams.
3. A method as set forth in claim 1 wherein said membrane is in the oral cavity, said carrier includes a mixture of starch disintegrating agent and flavor.
4. A method as set forth in claim 3 wherein said tablet comprises about 0.10 to about 99.0% by weight of ortho-ethoxybenzamide and the balance, to make 100% by weight, of said carrier.
